PREVENTING THE DEVELOPMENT OF SOURNESS IN CERTAIN PETROLEUM LIQUIDS DURING DISTILLATION

George W. Ayers, Chicago, Marcellus J. Geerts, Evanston, and Robert E. Chandler, Algonquin, Ill., assignors to The Pure Oil Company, Chicago, Ill., a corporation of Ohio

No Drawing. Application April 14, 1950,
Serial No. 156,036

10 Claims. (Cl. 196—29)

1

The present invention relates to the physical separation of specialty products from light petroleum distillates comprising parts of the gasoline and kerosene boiling range or both. It is more particularly concerned with a method for obviating the need for retreating special naphtha products which have been fractionally distilled from a naphtha feed stock, which has been sweetened in an oxidation treating process for mercaptan conversion prior to separating the special naphtha products.

The petroleum industry of today is no longer solely concerned with the production of fuels and lubricants. Due to the increased demand of manufacturers for solvents, chemicals and other articles of commerce available from the petroleum industry, the modern refining industry must be capable of diversification in its production of marketable products. The availability of petroleum hydrocarbons for chemical processing has given rise to the petrochemical industry which, in 1948, accounted for about 30 per cent of the production of synthetic organic chemicals. Although products which can be represented by specific chemical symbols are generally classified as petrochemical, what might be included as a facet of the petrochemical category of petroleum products are the hydrocarbon solvents, such as rubber solvent, V. M. and P. naphtha and Stoddard solvent. These particular specialty refinery products have long been well established solvents in various industries. The exacting and specialized needs of many manufacturers have required that these particular items be supplemented by other special petroleum naphtha products having boiling ranges especially designed to meet the specifications of individual consumers, or to suit a specific need. A few specific examples of these commercially available specialized petroleum products and their respective boiling ranges are as follows: Petroleum ether, 90°—140° F., special textile spirits, 180°—210° F., light mineral spirits, 290°—330° F., Stoddard solvent, 310°—385° F., high flash dry cleaning solvent, 360°—400° F. Such specialized products justify premium prices and have wide use in the protective coating industry, the natural and synthetic rubber industry, solvent extraction and other miscellaneous industries. Specific applications include use as solvents in paints, varnishes and lacquers; rubber cements and adhesives; extraction of fats—both vegetable and mineral. To meet the requirements of this growing demand, the potential naphthas contained in available crude stocks were found especially satisfactory.

2

The almost limitless variety of boiling ranges and solvencies available from a petroleum naphtha having a boiling range from about 225° to 425° F. obtained from a paraffin, naphthene or intermediate base crude makes its use as a feed stock to be employed in a special naphtha rerun unit which produces these special naphtha products ideal. Since straight run petroleum naphthas contain only small amounts of aromatic hydrocarbons and, as a result, are deficient in solvency qualities for such materials as resins, lacquers, and others, high solvency naphthas are produced from feed stocks that have been treated in various hydrocarbon conversion processes, such as hydroforming, to increase the aromatic hydrocarbon content of the naphtha. Thus, both aliphatic and aromatic type naphthas are made available.

The art of distillation and fractionation has been developed to such a degree that these specialized products are now produced quite readily in commercial units. Such products can sometimes be manufactured satisfactorily as side-stream cuts on crude distillation towers, but the more usual practice, where they are regular plant products, is their fractionation in special naphtha rerun units. In one typical unit, a petroleum naphtha distillate is separated by fractionation into an overhead stream, four side streams, and a residue. The overhead stream may be rubber solvent or low end point gasoline depending upon the characteristics of the charging stock. The four side streams are naphthas of various characteristics as desired. A more flexible type of special naphtha production is carried out in a superfractionation unit. This unit comprises a plurality of fractionating towers connected in series, said towers containing a large number of plates. In one particular superfractionation installation, two towers, a primary fractionating tower and a secondary fractionating tower, each containing 66 bubble trays, are used in series. Depending upon the boiling range desired in the final product, the required feed stock is passed to the primary fractionator. The overhead vapor from this tower is condensed, a portion going to storage and the remainder being returned to the primary fractionator as reflux. The bottoms from the primary fractionating tower passes to the secondary fractionator. Only one finished naphtha fraction is produced at a time and it is taken overhead as a "heart" cut from the secondary fractionating tower. Obviously, the overhead fraction from the primary fractionating tower may contain desirable naphthas, as may

the residue from the secondary fractionating tower. When this situation exists, the respective streams are placed in separate storage tanks and subsequently charged to the unit to produce the desired specification fraction in the established manner. A careful study of such factors as yield, purity, location of the optimum feed plate, location of fractions in the charge, and boiling points of distillates and residues is necessary in obtaining the required operating flexibility in these units.

Economics of the process and good operating procedure require that the thus produced distillate be ready for market without further treating. Although, in general, naphthas should be free from acidity, non-corrosive by the copper strip test, and free from gums or suspended matter, one of the rigid specifications required of the finished special naphtha is that it be free of the objectionable odor characteristic of lower boiling petroleum mercaptans. The absence of this odor is desired in order that the olfactory sense of the consumer not be disturbed by the marketed distillate, or in order that this odor not be imparted to any manufactured products containing these special naphthas. A specification test to indicate the presence of or freedom from these mercaptans which would cause this objectionable odor is the widely used so-called "doctor test." A sample of the product in which the doctor test gives positive results is deemed to contain these odoriferous mercaptans and is condemned as "sour." If the test is reported as negative, it is considered that the sample is substantially free from these odor-causing mercaptans and considered "sweet." The essence of this invention is, therefore, directed to conforming with the requirement of this standard specification by producing as a finished distillate from the naphtha rerun unit, a product requiring no further sweetening.

If the mercaptan content of the naphtha feed stock to rerun unit is not carefully controlled by proper refining, the special products fractionally distilled from this charge may be off specification. It has been reported that in order to produce a doctor negative or "sweet" product, the mercaptan content of the product must be at or below 0.0001 per cent by weight of mercaptan sulfur. The type crude available will of necessity dictate whether a sweetening process is a necessary adjunct to the naphtha rerun system. In processing a "sour" crude, i. e., one having a high sulfur content, in order to obtain marketable distillates, it is necessary that the distillates produced from these crudes be treated in one of the various light distillate treating processes available to the refining industry. These processes, in general, fall into three broad classifications: (1) oxidation processes, (2) mercaptan dissolving processes, and (3) catalytic desulfurization. The oxidation processes, in which the mercaptans present in the distillate are chemically converted to disulfides, produce a doctor sweet product which, due to the conversion of the foul-smelling mercaptans to less odoriferous disulfides, cannot be objected to olfactorily. Most common of this type process is the conventional sweetening with doctor solution. Other well known processes of this type are the copper chloride, hypochlorite, lead sulfide, and air oxidation in the presence of a catalyst, such as a phenolic type compound. Although this type of process is losing favor as a gasoline treating process because the disulfides harm the lead sus-

ceptibility of the gasoline and also because it is no longer considered necessary that marketable gasolines be doctor sweet, it does find considerable use as a naphtha treating process because the treated product does meet the required mercaptan sulfur content specification and gives a doctor negative product. The non-oxidizing type processes aforementioned have not found wide acceptance by the industry in the treating of naphthas, other than those which are used as a constituent in the blending of gasoline, inasmuch as they generally do not give a complete sweetening effect.

Having selected the oxidation type process as the more adaptable of the type processes available because of the ability to provide a complete sweetening effect, the efficacies of treating the naphtha charged to the rerun unit prior to rerunning or treating the finished products to give a doctor sweet product should be considered. While both practices are followed, it has been found that the method involving the treating of the naphtha feed stock prior to rerunning is more advantageous mainly because it saves scheduling of the treaters when a variety of specialized products are produced. When scheduling of the treaters is required, as is the situation when the finished product is treated, for each change in product there is an attendant loss of time and product involved due to changeover from one product to another. These difficulties are eliminated if the charge stock to the special naphtha rerun unit is treated, rather than the distillate produced. There is, however, a serious objection to this modus operandi that arises when the higher end point special naphthas are being produced. To effect these higher end point naphthas, higher operating temperatures are required. The distillate obtained under these conditions, although made from a doctor sweet feed stock, gives a doctor positive result and is, therefore, not acceptable because it does not conform with the mercaptan sulfur content specification. Before these products can be marketed, it is necessary to retreat the off-specification product. The advantages obtained by pretreating the feed stock are forced to lie in the penumbra of the disadvantages and remain unrecognized.

It is, therefore, an object of this invention to present a method of producing special naphthas that conform with the mercaptan sulfur content specification with a minimum of treating. Another object is to provide a method in which a doctor sweet distillate is manufactured without retreating the desired boiling range distillate after it has been fractionally distilled from a doctor sweet naphtha charge. A still further object is to provide a process for producing special naphtha fractions in which a petroleum naphtha distillate having a boiling range of from about 225° to about 421° F. is sweetened in an oxidation type process, said sweetened naphtha is then rerun in a special naphtha rerun unit to produce a specialty product that is doctor sweet without further treating. These and other objects are made apparent by the following exposition of our invention.

The objects of our invention are attained by the production of a doctor sweet special naphtha from a petroleum naphtha containing petroleum sulfur compounds including disulfides, without additional sweetening by effectuating the fractional distillation in the presence of an organic peroxide compound which conforms to the general formula, $R_1-O-O-R_2$, wherein R_1 is an

organic radical and R_2 is selected from the group consisting of an organic radical and hydrogen and which is stable against rapid decomposition at the temperatures reached in the distillation. Compounds contemplated by this invention are exemplified by organic peroxides, hydroperoxides, peracids, salts of peracids, perethers and peresters. It has been found that so long as the compound contains the peroxide linkage in its structure, it is effective to improve the efficiency of the distillation operations.

Specific examples of useful peroxides of the foregoing classes are as follows: di-tertiary-alkyl peroxides, such as di-tertiary-butyl peroxide, di-t-amyl peroxide, di-t-octyl peroxide, t-butyl pentamethylethyl peroxide, di-triethylmethyl peroxide, di-t-dodecyl peroxide, etc., tertiary-alkyl hydroperoxides, such as tertiary-butyl hydroperoxide, t-amyl hydroperoxide, t-octyl hydroperoxide, t-dodecyl hydroperoxide, etc., di-n-propyl peroxide, isopropyl hydroperoxide, di-sec-butyl peroxide, n-hexyl hydroperoxide, naphthene and unsaturated naphthene hydroperoxides and peroxides, such as 1-methylcyclohexyl-1 hydroperoxide, t-butyl 1-methylcyclohexyl-1 peroxide, 1-methyl-3-methylene cyclopentyl-2 hydroperoxide, 2,3-dimethyl cyclopentenyl-3 hydroperoxide, methyl cyclopentenyl peroxide, methyl 1-isopropyl-4-methylcyclohexenyl-3 peroxide, indane hydroperoxide, methyl indane peroxide, etc., terpene peroxides such as ascaridole, limonene hydroperoxide, pinene hydroperoxide, etc., hydrogenated naphthalene peroxides and hydroperoxides such as tetralin hydroperoxide, methyl tetralin peroxide, etc., aromatic peroxides, such as 1-phenylethyl-1 hydroperoxide, p-tolylmethyl hydroperoxide, etc., α -hydroxy and α,α' -dihydroxy, derivatives of peroxides and hydroperoxides such as α -hydroxyheptyl hydroperoxide, α -hydroxydodecyl hydroperoxide, α -hydroxynonyl hydroperoxide, hydroxy dicarbethoxymethyl hydroperoxide, α -hydroxyethyl methyl peroxide, α -hydroxymethyl ethyl peroxide, α -hydroxyethyl ethyl peroxide, α -hydroxyheptyl ethyl peroxide, α,α' -dihydroxydipropyl peroxide, α,α' -dihydroxydihexyl peroxide, α,α' -dihydroxydidecyl peroxide, α,α' -dihydroxydidecyl peroxide, α,α' -dihydroxydiisoamyl peroxide, di-(hydroxy - dicarbethoxy-methyl) peroxide, etc., peresters, such as t-butyl perbenzoate, t-butyl perstearate, t-butyl perundecylate, t-butyl diperadipate, t-butyl diperphthalate, t-amyl perbenzoate, dimethyl-, diethyl-, and diisopropyl - perterephthalates, trans-9-decalyl perbenzoate, etc., acyl peroxides, such as dibenzoyl peroxide, diphthalyl peroxide, dicamphoryl peroxide, etc., peracids, such as d-percamphoric acid, diperoxalic acid, perbenzoic acid, diperphthalic acid, etc., and various other peroxides, for example, peroxides of dioximes and derivatives thereof.

For the purpose of simplification of expression, the above compounds will be hereinafter referred to in the specification as organic peroxides.

Although the application of this invention is directed to the use of organic peroxides in general, there are obvious practical aspects that must be considered. Foremost is the inherent properties of some of these applicable organic peroxides to decompose rapidly and violently upon sudden heating or shock or both. Acetone peroxide, diacetil peroxide, diethyl peroxide, dimethyl fulvene peroxide, ethyl hydroperoxide, fumaryl peroxide, hexamethylene triperoxy di-

amine, methyl ethyl ketone peroxide, phthalyl peroxide, succinic peroxide, and succinyl peroxide are specific examples cited in the literature of organic peroxides that are unstable and dangerous to handle. In addition we have found that the metal salts of hydroperoxides and peracids are not suitable for the application to our invention. These metal salts show an extreme tendency to hydrolyze, are very explosive in the dry condition, and show little or no solubility in hydrocarbon liquids such as naphthas. These disadvantageous properties therefore also preclude the use of these compounds as suitable materials. Consideration at this point should also be given to the possible use of other than metal salts of the hydroperoxides or peracids such as the ammonium or substituted ammonium salts. The hydroperoxides possess weak acid characteristics and would therefore not readily be expected to form salts of this type. Peracids on the other hand because of the more acidic properties may form the ammonium or substituted ammonium type salts. The literature, however, makes no mention of the existence of these compounds and it is for this reason that these compounds are not considered within the class of operative materials employed by our invention. This invention is, therefore, directed to those relatively stable organic peroxide compounds that are comparatively safe to handle and whose solubility permits their use in operative proportions.

Obviously, no specific amount of organic peroxide that will cover all varieties of naphthas that would be processed in a rerun unit can be stipulated. The proportion of additive to be used in the process depends in part upon the quantity and quality of sulfur compounds present in the charge as well as practical considerations. In carrying out our invention, although we prefer to have present in the distillation zone while conducting the production of special naphthas one pound mole of organic peroxide for each 64 pounds of sulfur present in the naphtha feed stock as disulfide sulfur, the optimum quantity is best determined experimentally by making tests on samples of naphtha that are to be subjected to processing in the special naphtha rerun unit. Amounts as low as 0.001 per cent by weight of the distillate undergoing treatment in some instances are effective. It is well, however, in view of the possible attendant hazards that may result from the use of too large proportions of the organic peroxides, to maintain the upper limit of concentration in amounts not in excess of 0.5 per cent by weight. This limit is established as a safety measure, however, and is not to be construed as an operational limitation.

This aspect, as well as the essence of the invention, is shown by the following illustrative, but non-limiting, examples:

Example 1.—Three hundred milliliters of a doctor sweet naphtha stock having a distillation range between 256° F. and 438° F. and containing approximately 0.03 per cent by weight of disulfide sulfur (in addition to sulfur compounds other than mercaptans and disulfides) was subjected to distillation from a one-liter glass flask under conditions arranged to give considerable residence time of the naphtha charge in the flask during distillation. The distillate started to become sour to the doctor test when the temperature of the liquid in the flask was 350° to 360° F. In a similar distillation, except that 0.01 75 per cent by weight of benzoyl peroxide was also

present in the flask, the distillate began to give positive results to the doctor test only when the temperature of the liquid in the flask was 380° F.

Example 2.—When the distillation of sweetened long range naphtha stock was carried out as in Example 1, except that 0.01 per cent by weight of t-butyl hydroperoxide was substituted for the benzoyl peroxide, a sweet distillate was separated from the naphtha charge stock in the flask until the temperature of the liquid in the flask reached 383° F.

In further explanation of the foregoing examples it should be noted that these tests were conducted in a batch distillation. Commercial installations are generally operated continuously and under conditions whereby the feed is introduced to the fractionators and flash vaporized. This procedure, which is frequently taken advantage of in the art, enables the feed stock containing materials boiling below the temperature at which the feed is introduced to be fractionated and thereby produce an overhead product having a much higher end point than the temperature at which the flash vaporization was effected. This aspect is pointed out to show that although a maximum temperature of about 383° F. was attained in the above examples if advantage is taken of the mechanism of flash vaporization a naphtha product will be obtained as an overhead product from the fractionators used in the commercial manufacture of these special naphthas that will have a much higher end point than the temperature at which flash vaporization occurred, that is, the temperature at which the feed stock is introduced into the fractionation units. The success of this phenomenon depends, of course, on the presence in the feed of material of lower boiling point than said temperature.

It will thus be seen that we have succeeded in retarding the formation of mercaptans during distillation, thereby yielding a sweet distillate having a higher end point than the distillate obtained when the distillation is carried out in the absence of the organic peroxide compounds of our invention.

In carrying out the teachings of this invention, the effective amounts of organic peroxide may be introduced into the fractionation zone by using the naphtha feed as a carrier or direct injection into the distillation zone. Where direct introduction is employed as the method of application, it is preferable to use a solution of the selected organic peroxide in a compatible solvent, such as the feed stock to the unit. The residue from the fractionating towers will contain any residue organic peroxide employed as the distillation agent from which it may be recovered, for re-use, by any suitable means.

The mechanism of the phenomenon attributable to our invention is not readily explained. The obvious cause of the sour distillate produced from a naphtha charge stock which has been sweetened in an oxidation type sweetening process when the teachings of our invention are not followed is that mercaptans are formed during the distillation operation. Mercaptan formation by the cleavage of disulfides is well known and this indubitably accounts for a certain amount of the mercaptans present in the sour product, although other modes of mercaptan formation from sulfur compounds present other than the disulfides may also account for the presence of mercaptans in critical amounts sufficient to produce a sour distillate. We have found, however, that it is possible to inhibit this detrimental sour-

ness by carrying out the distillation process in the presence of small amounts of an organic peroxide.

It will be seen, therefore, that we have been successful in providing a method whereby it is possible to separate from a naphtha feed stock, which has been sweetened in an oxidation type sweetening process, by fractional distillation in the presence of an organic peroxide, a sweet distillate having a higher end point than a similarly produced distillate having been separated in a distillation process in which an organic peroxide was not used.

Having substantially disclosed our invention, we therefore claim:

1. A method for inhibiting the increase in mercaptan content of light petroleum distillates containing organic sulfur compounds including disulfides during heating thereof comprising the heating in the presence of a small amount of a relatively stable organic peroxide selected from the group consisting of tertiary butyl hydroperoxide and benzoyl peroxide at temperatures conducive to organic disulfide decomposition

20 but below those temperatures at which the said disulfides decompose in the presence of said peroxides.

2. A method in accordance with claim 1 in which the peroxide is benzoyl peroxide.

30 3. A method in accordance with claim 1 in which the hydroperoxide is tertiary butyl hydroperoxide.

4. A method for separating by fractional distillation a petroleum naphtha, said naphtha having been subjected to a sweetening process wherein petroleum mercaptans contained in said naphtha are converted to disulfides, which comprises conducting the distillation in the presence of a small amount of relatively stable organic

35 peroxide selected from the group consisting of tertiary butyl hydroperoxide and benzoyl peroxide at temperatures conducive to organic disulfide decomposition but below those temperatures at which the said disulfides decompose in the presence of said peroxides to produce a distillate having a mercaptan-sulfur content of not more than about 0.0001 per cent by weight and having an end point which is of a higher degree of temperature than it is possible to obtain in the absence of said organic peroxide.

50 5. A method in accordance with claim 4 in which the peroxide is benzoyl peroxide.

6. A method in accordance with claim 4 in which the hydroperoxide is tertiary butyl hydroperoxide.

55 7. In a method for heating sulfur-containing, doctor sweet, petroleum distillates boiling within the temperature range of about 250° and 450° F. to a temperature at which formation of mercaptans is induced, the step of inhibiting said mercaptan formation comprising conducting the heating in the presence of a relatively stable organic peroxide selected from the group consisting of tertiary butyl hydroperoxide and benzoyl peroxide, said organic peroxide being present in the ratio of 1 pound molecular weight for each sixty-four (64) pounds of sulfur, calculated as disulfide sulfur, present in the said petroleum distillate, at temperatures conducive to organic disulfide decomposition but below those temperatures at which the said organic disulfides decompose in the presence of said peroxides.

70 8. A method in accordance with claim 7 in which the organic peroxide is tertiary butyl peroxide.

9. A method in accordance with claim 7 in which the organic peroxide is benzoyl peroxide.

10. A process for fractionally distilling a petroleum naphtha feed stock containing petroleum sulfur compounds including said disulfides to produce a plurality of distillates, said distillates respectively having a narrower boiling range than said naphtha feed stock, the improvement which comprises conducting said distillation in the presence of a small amount of a relatively stable organic peroxide selected from the group consisting of tertiary butyl hydroperoxide and benzoyl peroxide, at temperatures conducive to organic disulfide decomposition but below those temperatures at which the said disulfides decompose in the presence of said peroxides, whereby the mercaptan content of the separated

distillates is maintained at an amount less than the mercaptan content of distillates produced from the same said naphtha feed stock by fractional distillation in the absence of the aforesaid organic peroxide.
